United States Patent Office

Des. 193,280
Patented July 24, 1962

193,280

JUG OR THE LIKE

Clara Virginia Eicholtz, Midland, Mich., assignor to The Dow Chemical Company, Midland, Mich., a corporation of Delaware

Filed Nov. 17, 1961, Ser. No. 67,572

Term of patent 14 years

(Cl. D58—5)

Fig. 1

Fig. 2

The decorated band about the bottom is continuous.

I claim:

The ornamental design for a jug or the like, as shown and described.
